ATTORNEY

UNITED STATES PATENT OFFICE.

JAMES K. STOCKTON, OF BROOKLYN, NEW YORK.

SOFA-BED.

SPECIFICATION forming part of Letters Patent No. 251,742, dated January 3, 1882.

Application filed June 7, 1881. (No model.)

To all whom it may concern:

Be it known that I, JAMES K. STOCKTON, of Brooklyn, county of Kings, and State of New York, have invented certain new and useful 5 Improvements in Sofa-Beds, of which the following is a specification.

This invention relates to an improved construction of bed-lounge or sofa-bed in which the hard and unyielding ridge which is at present formed at the meeting edges of the hinged seat-sections is done away with, the construction simplified, and the operation of changing the parts from a sofa or lounge into a bed, and vice versa, accomplished with great ease and 15 facility.

The invention consists of a supporting-frame the back of which is recessed between the posts below the edge of the upholstered section, so as to provide a space for the storing away of the 20 rear section of the seat, which section is pivoted by bracket-arms to the frame. The springs of the rear section are connected by links to the springs of the main or front section of the seat. The main section is guided by rails at the under 25 side in recesses at the front piece of the main frame, its forward motion being stopped by the contact of the brackets of the rear section with fixed side pins of the frame. The head-piece forms one piece with the front section of the 30 seat, so as to move forward therewith, while the head-piece of the hinged rear section of the seat is pivoted at its upper end to the sofa-frame, and composed of two hinged sections, which are retained in raised position by a rail or seat of the 35 rear section of the seat and in lowered position by a transverse stop or rail of the sofa-frame.

In the accompanying drawings, Figure 1 represents a plan view, with parts broken away, of my improved sofa-bed shown as drawn out for 40 use as a bed. Fig. 2 is a front elevation of my improved sofa-bed folded up. Figs. 3 and 4 are vertical longitudinal sections through the head-piece and seat, showing the former respectively when folded and drawn out. Figs. 5 and 6 are vertical transverse sections of the sofa-bed in folded and open positions; and Fig. 7 is an 45 end elevation of the sofa-bed, with a part broken away to show the construction of the rear head-piece.

50 Similar letters of reference indicate corresponding parts.

A in the drawings represents the supporting-

frame of my improved sofa-bed or bed-lounge, and B the back of the same, which is recessed or open between the hind feet of the frame, below the upholstered upper portion, as shown in Fig. 5, so as to provide room for the storing away of the rear section, C', of the seat. The frame of the front section, C, of the seat is provided at the under side with rails *a*, which are 55 guided in recesses of the front piece of the sofa-frame A. The frame of the seat-section C is made in one piece with the head-piece D, and provided with legs and moldings which are in line with the front legs of the sofa-frame 60 A, so as to cover the latter when the seat-section is moved back for forming a sofa or lounge. The main section C of the seat, as well as the rear section, C', is cushioned by springs and an upholstered covering, which latter extends continuously from the main section C over the rear section, C'. The adjoining rows 65 of springs of sections C C' are coupled or jointed together by means of wirelinks *b*, which admit the swinging down of the rear section, C', into the open recessed part of the main frame A, below the upholstered back B, as shown in Fig. 5, or the swinging up of the rear section to a level with the main section, as shown in Fig. 6. For this purpose the frame 70 of the rear section, C', is connected by end brackets, *d*, to pivots *d'* of the end pieces of the main frame A, so that by pushing the main section C inwardly toward the back B the rear section, C', is thrown around the pivots into 75 vertical position, while by drawing out the main section C the rear section is carried up by the link-connection of the section until its end brackets are stopped by stop-pins *e*, or equivalent devices, as shown in Fig. 6. In this 80 latter position the connecting-links of the springs of the seat-sections C C' are stretched, and thus a horizontal connection of the seat-sections obtained without the objectionable 85 ridge formed in the sofa-beds heretofore in use at the meeting edges of the seat-sections. As the forward and backward motion of the main section on the main frame A governs the swinging motion of the rear section, C', it will be 90 readily perceived that the operation of adjusting the sofa to a bed, and vice versa, is extremely simple, and can be performed by every one with great facility without requiring any 95 extra exertion or special knowledge.

As the head-piece D of the sofa is made in one piece with the main section C of the seat and moved forward and backward with the same, a second head-piece, D', has to be arranged to be used in connection with the rear section, C', when the main section C is drawn out. The second head-piece, D', is pivoted at its upper end to the main frame A, and made of two parts—an upper smaller one, f, 10 and a lower longer one, f'—which are hinged together, and are covered by a continuous upholstering. The lower part, f', is provided at the lower edge with a loop, f², for handling the same in raising or lowering the parts. When 15 the main seat-section C and head-piece D are drawn out the loop is taken hold of and the lower part, f', of the lower head-piece, D', raised from its lowermost position, as shown in Fig. 3, into the raised position shown in Fig. 4, in 20 which position the lower recessed part of the same engages a rail or seat, f³, at the end of the rear section, C', of the seat. The hinged parts f f' of the head-piece D' assume thereby an angular position to each other, as shown in 25 Fig. 4, while they are in line with each other when lowered, as shown in Fig. 3, in which case the lower section is retained by a suitable transverse stop-rail, f⁴. After the main section C has been drawn out, the rear head-piece, 30 D', is raised in the manner described until it is in line with the main head-piece D and fills entirely the space between it and the back B of the sofa, forming thus the head-piece for the rear section of the seat. When the seat-section C is returned into position so as to form 35 a sofa the main head-piece D covers the rear head-piece, D', which has been lowered below the same, so as to be entirely out of sight. In this manner an easily-operated, convenient, 40 and inexpensive sofa or lounge bed for domestic purposes is obtained.

Having thus described my invention, I claim as new and desire to secure by Letters Patent—

1. The combination, in a sofa or lounge bed, 45 of a main frame, A, having a back, B, which is

open or recessed below the upper upholstered section, with a movable main section, C, having a rear section, C', jointed to the main section and adapted to be thrown into the open back of the main frame or raised to a level with the drawn-out main section of the seat, substantially as set forth. 50

2. The combination, with the main frame A, of the sliding and guided seat-section C, made in one piece with its head-piece D, and provided with a swinging rear section, C', jointed thereto, substantially as specified. 55

3. The combination of the main frame A and back B, having an open lower part, with a sliding seat-section, C, having a head-piece, D, made in one piece therewith, hinged rear section, C', jointed to the main section and pivoted to the main frame A, and with an adjustable rear head-piece, D', which is adapted to be raised or lowered as required, substantially as set 60 forth. 65

4. The combination, in a sofa or lounge bed, of the main frame A and back B, having a lower open part, with a sliding main seat, C, pivoted and jointed rear section, C', connected by bracket-arms to pivots of the main frame and adapted to be stopped by pins of the same, substantially as and for the purpose set forth. 70

5. The combination, in a sofa or lounge bed, with the main frame A, of a rear piece, D', composed of two parts, f f', which are hinged together, the upper part being pivoted to the main frame and the lower adapted to be retained on a rail or seat, f³, of the rear seat-section, or a rail, f⁴, of the frame A, substantially 75 80 as described.

In testimony that I claim the foregoing as my invention I have signed my name, in presence of two witnesses, this 12th day of April, 1881.

J. K. STOCKTON.
